MOTOR FOR CLOTHES WASHERS

Royal D. Edsell, Pelham Manor, N. Y.

Application November 8, 1932, Serial No. 641,747

3 Claims. (Cl. 121—164)

One of the objects of this invention is to provide a mechanical clothes washing device which will be automatic in its operation, whereby it will not require the services of an operator.

5 Another object is to provide a device of this character that preferably will be operated entirely by fluid pressure, such as water obtained directly from a suitable faucet.

10 A further object is to provide a light portable device of this character that will be complete in itself and so designed that it will fit into any stationary laundry tub or similar vessel, with which every home and apartment is equipped.

15 With these and such further objects in view as will be apparent as the description proceeds, the invention consists of the following construction, combination and arrangement of parts hereinafter disclosed in the specification, reference being had to the accompanying drawings 20 forming a part hereof and wherein a preferred embodiment of the invention is shown though it is to be understood that such changes, variations and modifications as may fall within the scope of the claims hereinafter appended are within 25 the purview of my invention.

In the drawings.

Figure 1 is a plan view of the machine.

Figure 2 is a transverse section on the line 2—2 of Figure 1.

30 Figure 3 is a front elevation of the device.

Figure 4 is a transverse section on the line 4—4 of Figure 1.

35 Figure 5 is an enlarged detail plan showing the manner in which the valve actuator functions in accord with the position of the drive gear segment.

Figure 6 is an enlarged detail section showing the manner in which the water supply hose is attached to a water faucet.

40 As shown in the accompanying drawings, a cylinder, preferably of the hydraulic type, is indicated at 18 and is provided with a head 11 and rear wall 12 connected together by suitable stay bolts 13. The lower portion of said cylinder is provided with flanged extensions suitably fastened to a horizontal supporting plate 14 by means of screws or bolts 15. The piston rod 17 extends through a suitable packing nut 18, the piston rod being pivotally fastened to a link 19 secured to a rack bar 20 provided with the usual teeth 21. Rack bar 20 is guided in its movement by guides 22 secured to plate 14.

45 An agitator drive shaft is indicated at 23. Said drive shaft extends through the plate 14 and is rotatably mounted in a post 24 carried

by said plate 14. The drive shaft 23 carries an agitator 24 which is vertically slidable thereon and which is so mounted on said shaft as to be rotatable therewith but not independently thereof. The agitator 24 is provided with downwardly depending stirring blades 25 and said agitator is constructed of a buoyant material whereby it will float at all times on the surface of the water containing the material to be washed or otherwise treated. The lower end of shaft 10 23 carries a stop collar 26 to prevent the agitator 24 from slipping from said shaft.

50 Mounted on the upper end of the shaft 23 is a segmentally-shaped gear 27, the teeth of which mesh with the teeth 21 of the rack bar 20. Said gear 27 carries posts 28 to which arms 29 are pivoted each carrying a pin 30 to which a rod 31 is secured. The opposite ends of said rods 31 loosely extend through bearing pins 32 secured to a valve actuator 33 which is provided in its periphery with notches or shoulders 34. The valve actuator 33 is carried by a valve shaft 35 which is rotatably mounted in the body of a valve 36 and extends through a packing nut 36'. Said shaft supports a four-way valve 37. A water or other fluid inlet pipe for the valve 36 is indicated at 38 and an outlet or discharge pipe from said valve is indicated at 39. The inlet pipe 38 may be connected by a suitable hose 40 (see Fig. 6) to a member 41 supporting a rubber gasket 42, a lock nut 43 being also provided and adapted to be held in its proper position by means of a threaded member 44 which may be fastened to any suitable water faucet 45 by means of two or more pointed set screws 46.

55 The valve casing 36 carries a pivoted lever or detent 47 the lower part of which carries a compression spring 48 having the effect of tending to force the upper end of the lever or detent into engagement with the peripheral edge of the valve actuator 33 and against one of the shoulders or notches 34 to limit the degree of rotation of said valve actuator 33. Each of the rods 31 also carries a compression spring 49 bearing against their respective pins 30 and 32 and tending by their action to rotate the valve actuator 33 in either one of its extreme positions and to maintain the end of the lever or detent 47 in engagement with either one of the shoulders 34. The segmentally-shaped gear 27 also has secured thereto dogs or trips 50 either of which, upon rotation of said gear to one of its extreme positions, is adapted to engage the lower end of the pivoted detent 47 to trip the same against the action of the spring 48 and thereby release said detent 47 from its engagement with 55

either one of the shoulders 34. This action forces the valve actuator 37 to rotate by the action of one of the springs 49 and changes the position of the valve 37 in an obvious manner. At the end of 5 the rotary movement of said valve actuator just described the detent 47 will engage against the other of said notches or shoulders 34 and hold the valve 37 in its new position and until the gear 27 has again been rotated to its extreme position in 10 the opposite direction.

The horizontal supporting plate 14 carries a vertically extending safety cover or plate 51 slotted as indicated in Fig. 3 to permit reception of the ends of the rods 31 during their movements and it 15 is also slotted to receive the inlet pipe 38. The supporting plate 14 also has fastened thereto bracket portions 52 the ends of which are U-shaped to conform in shape to the upper side edges 20 of a laundry tub the righthand brackets being hinged as at 52' and being also provided with set screws 53 for tightening purposes. The lefthand brackets 52 are preferably slidably fastened to the supporting plate 14 and adjustable as to their position in connection therewith by means of the 25 winged nuts 54 thereby permitting variation of the width of the device as a whole to conform to the width of the laundry tub to which it is to be applied. Valve 36 is connected by a pipe 55 to the forward end of the cylinder 10 and also by a pipe 30 56 to the rear of the cylinder 10.

The operation of the device is as follows:

The machine is suspended by means of the U-shaped bracket portions 52 within a laundry tub and connection is made with a suitable hydrant 35 or water faucet 45 to the inlet pipe 38 by means of the rubber hose 40. The water, soap and materials to be washed are then placed in the tub and the connections with the water faucet or hydrant are opened. The water from the faucet may be 40 made to flow in any desired volume and pressure through the inlet pipe 38 and through the four-way valve 31. This water is diverted by said valve through the pipe 55 through which it is carried to the forward end of the cylinder 10 and creates a pressure against the piston head 16 forcing said 45 piston head to move rearwardly in said cylinder. If the cylinder at the rear of said piston head contains water this exhaust water from the cylinder is forced through the pipe 56 to the four-way valve and is diverted by said valve through the exhaust 50 or outlet pipe 39 from which it may be carried by an outlet or waste hose (not shown) and to an adjoining laundry tub, sink or sump. As the piston head is forced rearwardly by pressure of water 55 thereagainst, rack 20 is in consequence moved in the same direction. The teeth 22 of said rack, inasmuch as they mesh with the teeth of gear segment 27 causes said segment to rotate with its shaft 23 which rotates the agitator 24' to thereby 60 agitate or stir up the water and materials therein and contained in the tub. As the piston travels to its extreme rearward position the segment 27 likewise rotates in a clock-wise direction (Fig. 1) to 65 compress the left-hand spring 49. When the extreme rearward position of the piston has been reached the right-hand trip or dog 50 on the gear segment 27 trips the detent 47 to release it from the shoulder 34 on the valve actuator 33 which it 70 engages. This action produces a quick rotation of said valve actuator in a clockwise direction by the action of the left-hand spring thereby reversing the position of the valve 37 and permitting the detent 47 to engage against the opposite shoulder of the valve actuator 33. Water then flows

from the inlet pipe 38, through the valve 37, through the pipe 56 and to the rear of the cylinder 10 thereby exerting pressure against the rear of the piston head 16 to move it forwardly in its cylinder and forcing the water in the forward portion of 5 said cylinder through the pipe 55, valve 37 and from the outlet or discharge pipe 39. The device may be operated automatically and continuously, in an obvious manner, the parts being actuated by the water pressure against the front or rear of the piston head as the case may be to actuate the movable parts and to eject water from the cylinder in the manner heretofore explained.

Various modifications may be resorted to without departing from the spirit of the invention as 15 set forth in the appended claims.

The invention claimed is:

1. In a clothes washer having a cylinder, a piston therefor, a rack connected to said piston, and a rotatable gear member at one side of said cylinder, said gear member meshing with said rack, an automatic control therefor comprising a valve positioned on the opposite side of the gear member from said cylinder and connected to opposite ends thereof for controlling the admission of fluid 20 to said cylinder and the discharge of fluid therefrom, a valve actuator connected to said valve, means on said gear member connected to said valve actuator and tending to move said valve actuator to change the position of said valve, means pivoted upon a fixed part of the valve acting to retain said valve in a given position and means carried by said gear member adapted to trip said retaining means for permitting said valve to assume a different position.

2. In a clothes washer having a cylinder, a reciprocating piston therein, a rack connected to said piston, a gear meshing with said rack, and an automatic control therefor comprising a valve positioned on the opposite side of said gear 40 member from said cylinder and connected to opposite ends of the cylinder for controlling the admission of fluid to said cylinder to either end of said piston, a valve actuator connected to said valve and provided with a shoulder thereon, a spring-pressed detent pivoted upon a fixed part of the valve 45 adapted to be engaged with said shoulder, spring means connecting said gear and valve actuator and tending by its action to move said valve actuator to change the position of said valve and a dog fastened to said gear for tripping said detent to permit said spring means to function.

3. In a portable clothes washing machine having a support adapted to be suspended on the sides of a tub or other receptacle and comprising a cylinder connected to said support, a reciprocating piston in said cylinder, a piston rod connected to said piston, a rack bar pivotally connected to said piston rod, guide means on said support for guiding the movement of said rack bar, a gear meshing with said rack bar, a valve mounted on said support, a valve actuator connected to said valve, rods connected to said gear and slidably connected to said valve actuator, compression springs carried by said rods, a spring-pressed detent normally holding said valve actuator in a given position and dog members carried by said gear and adapted to trip said detent to permit movement of said valve actuator by the action of one of said springs and effect a change of position of said valve.

ROYAL D. EDSSELL.
